**RACE SIMULATING GAME HAVING INTER-
CHANGEABLE TRANSMISSION UNITS OF
VARIOUS SPEED RATIOS**

Alfred A. Caputi, 71 Parkdale Ave., Buffalo, N.Y.
Filed Mar. 4, 1963, Ser. No. 262,456
11 Claims. (Cl. 273—86)

This invention relates to a game or amusement device and more particularly to a game which simulates racing wherein a number of racing figures such as race horses or racing cars travel about a race course.

The present invention comprises a game board or support surface which includes a closed racing course which may be of various configurations such as circular, oblong, elliptical or the like. Racing figures which simulate race horses, racing cars or other racing figures are caused to move about the race course and means disposed beneath the game board or support surface propel the several racing figures about the race course.

In the form shown herein by way of example, the propelling means beneath the game board or support surface acts upon the racing figures magnetically through the game board or support surface but various other means may be employed for this purpose including direct mechanical connection between the propelling means and the racing figures.

Speaking generally and broadly, the present invention provides propulsion means whereby a number of racing figures are caused to move about the race course at different speeds and by means of an arrangement which renders it impossible for the players to know beforehand the order in which the racing figures will finish. In the racing game arrangement of the present invention a single power source drives the various propulsion devices which activate the racing figures.

In accordance with the present invention, a number of readily removable speed changing transmission devices are provided corresponding to the number of racing figures. These transmission devices are generally enclosed and are substantially identical in external appearance and shall be referred to herein as capsules. The several capsules may readily be removed from the apparatus and reshuffled or rearranged in a random fashion so that, when replaced, each will transmit propulsion forces to one of the racing figures. However, it will not be known to the players which of the figures is connected with each of the several transmission devices of various output ratios.

A full understanding of the principles of operation and use of the racing game of the present invention will be had from a consideration of the typical embodiment illustrated in the accompanying drawings and described in detail in the following specification. However, it is to be understood that such embodiment is by way of example only and the scope of the invention is not limited thereto nor otherwise than as defined in the appended claims.

Various objects and advantages of the present invention will appear to those skilled in the art from a perusal of the specification in conjunction with the accompanying drawings.

In the drawings:

FIG. 1 is a general top plan view of one form of the racing game of the present invention;

FIG. 2 is a cross-sectional view on the line II—II of FIG. 1;

FIG. 3 is a cross-sectional view taken approximately on the line III—III of FIG. 2 with portions thereof shown in elevation for simplicity of illustration;

FIG. 4 is a fragmentary cross-sectional view on the line IV—IV of FIG. 2;

FIG. 5 is a disassembled perspective view of a portion

of the central hub structure of the drive means illustrated in FIG. 2; and

FIG. 6 is a fragmentary elevational view of one of the racing figures of the form of invention illustrated herein.

5 Like characters of reference denote like parts throughout the several figures of the drawings. It is to be understood that the racing game of the present invention may assume various physical forms and that the specific arrangement shown in the drawings merely illustrates the general principles of the invention.

In the form shown herein the game comprises generally a box-like structure comprising a frame 10 which forms side and end walls and includes a bottom wall 11 and an upper panel 12 whose upper surface is marked to define

15 an oblong race course 13. In FIG. 2 the numeral 14 designates a racing figure shown in front edge elevation which figure may simulate a race horse or other racing figure and the lower edge of FIGURE 14 includes a permanent magnet insert 15. As shown in FIG. 6 magnet

20 15 is formed to provide longitudinally spaced north and south poles and a companion magnet member 16 beneath the panel 12 is similarly formed whereby the magnets cooperate to maintain the figure 14 in a properly aligned position with respect to the race course 13.

25 The underside of panel 12 is provided with a series of spaced parallel rails 20 which define racing lanes of a race course comprising semi-circular end portions and connecting straightaway portions. As shown in FIG. 2, the lower magnet members 16 are generally guided in the lanes 30 formed by rails 20 and the manner in which magnets 16 are supported will be described later herein.

Referring to FIG. 2, a pair of crossed metal strap members 22 and 23 are fixed to lie upon the bottom wall 11 and a support for the drive means of the racing game of

35 the present invention comprises an inverted cup-shaped member 24 which is notched at 90° intervals to interlock with the strap members 22 and 23 to be located thereby. The numeral 26 designates a series of internal gear members which have complementary offset radial faces which

40 interfit as clearly shown in FIG. 2 for retaining the several internal gears in axially aligned relationship and the lowermost internal gear member 26 seats in an annular recess formed in the upper surface of cup-shaped member 24. The internal gears 26 are each grooved at their outer 45 periphery to receive V belts 28. Referring to FIG. 1, the numeral 30 designates an axially aligned vertical series of idler pulleys which are supported for free rotation relative to each other in any desired manner and the V belts 28 extend about the internal gear members 26 and pulleys 50 30 to be driven by the former in a path parallel to the paths of the racing lanes.

Each belt 28 has fixed thereto an arm 32 which extends perpendicularly outwardly from the belt and terminates in an upwardly extending portion 33, the magnet 16 being 55 fixed to the upper ends of the portions 33 of arms 32. From the foregoing it will be seen that driving rotation of each internal gear 26 causes the associated magnet 16 to traverse a desired racing path and the traction between the magnets 15 and 16 causes the associating racing figure 60 to likewise traverse this path in proper alignment therewith.

The means for variably driving the several internal gears 26 will now be described. Referring to FIG. 2, a hollow drive shaft 35 is rotatably supported at its lower 65 end in the upper wall of cup-shaped support member 24. A spiral spring 36 is attached at its inner end to shaft 35 and at its outer end to cup-shaped member 24 as at 37. A dial plate 40 has a central counterbore at its underside including keyways which engage keys 72 70 projecting from keyways 44 in shaft 35, as will be described more fully later herein. Finger holes 45 in dial

40 are engaged to wind spring 36, in the present instance, in a clockwise direction.

A ratchet wheel 50 is fixed to crossed straps 22 and 23 and a pawl 51 engages the teeth of ratchet wheel 50 to prevent retrograde counterclockwise movement of shaft 35 until such movement is desired. Pawl 51 includes a stem portion 52 which is mounted in the lower end of hollow shaft 35 for radial sliding movement and is normally urged to the left as viewed in FIG. 4 to retain pawl 51 in engagement with the teeth of ratchet wheel 50 by a spring 54.

An enlargement 56 on stem 52 is beveled for camming engagement with a nose member 57 at the lower end of a rod 58 which extends upwardly through shaft 35. An operating knob 60 carried by dial plate 40 fits over the upper end of rod 58 and is normally held in a raised position by a spring 61. When knob 60 is depressed with spiral spring 36 in a wound condition nose 57 moves stem 52 and pawl 51 to the right as viewed in FIGS. 2 and 4 to free the shaft 35 for rotation by spring 36 in a counterclockwise direction as viewed in the drawings.

Reference will now be had to readily removable and interchangeable transmission capsules of various speed change ratios which act between shaft 35 and the several internal gears 26 during an actual race period. Each capsule comprises a disk 64 having a pair of intersecting circular recesses formed in its upper face to receive, respectively, a sun gear 65 and a planet pinion 66. A cover plate 67 may be cemented or otherwise affixed to the top of each disk 64 to enclose the gear 65 and pinion 66, both of which rotate within their respective circular recesses in disk 64. Both the disk 64 and cover plate 67 may be of molded plastic material and the internal gears 26 may likewise be of molded plastic material.

All of the internal gears 26 are of the same pitch diameter and have teeth of the same size and number. All of the five spun gears 65 have different pitch diameters and numbers of teeth and the related planet pinions 66 also of course vary as to pitch diameter and number of teeth since the pitch radius of each sun gear plus the pitch diameter of the related planet pinion must equal the pitch radius of the internal gears which are all equal. Thus rotation of the five sun gears in unison rotates the five internal gears 26 at five different speeds.

Shaft 35 has opposed keyways 44 and a member designated generally by the numeral 70 in FIG. 5 comprises a base collar 71, a pair of upstanding keys 72, and an upper connecting member 73. Base collar 71 seats upon the bearing in cup-shaped member 24 and keys 72 seat in keyways 44, projecting therefrom to enter keyways formed in the several sun gears 65.

From the foregoing it will be seen that users of the game may lift dial 40 from its operative illustrated position, grasp the top cross member 73 of member 70 and thereby lift all of the transmission capsules out of their assembled positions in the internal gears 26. Note that the lowermost capsule disc 64 rests upon base collar 71 of member 70.

The players will then shuffle the capsules about and assemble them in a stack in random order. Since they all appear the same externally the players will not know their sequence as far as their various speed ratios are concerned. They will then be replaced on the keys 72 of member 70 and the latter will be returned to its assembled position as shown in FIG. 2. Thereupon dial 40 may be replaced with its keyways in engagement with keys 72 and the spring 36 may be wound to any desired extent. The figures may all be aligned in a starting gate or multiple stall member 76 in registry with the several arms 32 and the race is started by pressing knob 60 to release shaft 35.

I claim:

1. In a racing game, a support surface having a closed race course at its upper surface with figures movable thereon to traverse such race course, coaxial internal gears and means extending from each of said gears to one

of said figures for propelling the latter upon rotation of the former, a drive shaft extending axially through the internal gears and means for rotating the same, and a plurality of transmission devices each adapted to lie generally in the plane of and within the confines of one of said internal gears to establish driving connection between said drive shaft and such internal gear, said several transmission devices each having a central sun gear slidably keyed to said drive shaft and a planet pinion meshing with said sun gear and the related internal gear, the several pairs of sun gears and planet pinions being of different drive ratios, said internal gears being of the same pitch diameter and tooth size and said transmission devices being readily removable and interchangeable whereby the resultant speed of the several figures in any random arrangement of the transmission devices is unknown to the players of the game.

2. In a racing game, a support surface having a closed race course at its upper surface with figures movable thereon to traverse such race course, coaxial internal gears and means extending from each of said gears to one of said figures for propelling the latter upon rotation of the former, a drive shaft disposed within the internal gears and means for rotating the same, and a plurality of transmission devices each adapted to establish driving connection between said drive shaft and an internal gear, said several transmission devices each having a central sun gear slidably keyed to said drive shaft and a planet pinion meshing with said sun gear and an internal gear, the several pairs of sun gears and planet pinions being of different drive ratios, said internal gears being of the same pitch diameter and tooth size and said transmission devices being readily removable and interchangeable whereby the resultant speed of the several figures in any random arrangement of the transmission devices is unknown to the players of the game.

3. In a racing game, a support surface having a closed race course at its upper surface with figures movable thereon to traverse such race course, coaxial internal gears and means extending from each of said gears toward one of said figures for propelling the latter upon rotation of the former, a drive shaft extending within the internal gears and means for rotating the same, and a plurality of transmission casings each adapted to lie generally in the plane of and within the confines of one of said internal gears, said several transmission casings each having a central sun gear slidably keyed to said drive shaft and a planet pinion meshing with said sun gear and the related internal gear, the several pairs of sun gears and planet pinions being of different drive ratios, said internal gears being of the same pitch diameter and tooth size and said transmission casings being readily removable and interchangeable whereby the resultant speed of the several figures in any random arrangement of the transmission casings is unknown to the players of the game.

4. In a racing game, a support surface having a closed race course at its upper surface with figures movable thereon, coaxial internal gears and means extending from each of said gears to a point beneath one of said figures, said extending means and said figures having magnetically attractive portions whereby movement of the extending means propels the figure about the race course, a drive shaft extending within the internal gears and means for rotating the same, and a plurality of transmission devices each adapted to lie generally in the plane of and within the confines of one of said internal gears to establish driving connection between said drive shaft and such internal gear, said several transmission devices each having a central sun gear slidably keyed to said drive shaft and a planet pinion meshing with said sun gear and the related internal gear, the several pairs of sun gears and planet pinions being of different drive ratios, said internal gears being of the same pitch diameter and tooth size and said transmission devices being readily removable and interchangeable whereby the resultant speed of the several

figures in any random arrangement of the transmission devices is unknown to the players of the game.

5. In a racing game, a support surface having a closed race course at its upper surface with figures movable thereon to traverse such race course, coaxial internal gears and means extending from each of said gears to one of said figures for propelling the latter upon rotation of the former, a drive shaft extending axially through the internal gears and means for rotating the same, and a plurality of similar transmission devices each adapted to lie generally in the plane of and within the confines of one of said internal gears to establish driving connection between said drive shaft and such internal gear, said several transmission devices having various speed ratios as between said drive shaft and the related internal gear, said transmission devices being readily removable and interchangeable whereby the resultant speeds of the several figures in the case of any chance arrangement of the transmission devices is unknown to the players of the game.

6. In a racing game, a support surface having a closed race course at its upper surface with figures movable thereon to traverse such race course, coaxial internal gears and means extending from each of said gears to one of said figures for propelling the latter upon rotation of the former, a drive member and means for rotating the same, and a plurality of similar transmission devices each adapted to lie generally in the plane of one of said internal gears to establish driving connection between said drive member and such internal gear, said several transmission devices having various speed ratios as between said drive member and the related internal gear, said transmission devices being readily removable and interchangeable whereby the resultant speeds of the several figures in the case of any chance arrangement of the transmission devices is unknown to the players of the game.

7. In a racing game, a support surface having a closed race course at its upper surface with figures movable thereon to traverse such race course, coaxial internal gears and means thereon extending to points beneath said figures, said extending means and said figures having magnetically attractive portions whereby rotation of said gears propels the figures about the race course, a drive shaft extending within the internal gears and means for rotating the same, and a plurality of similar transmission devices each adapted to lie generally in the plane of and within the confines of one of said internal gears to establish driving connection between said drive shaft and such internal gear, said several transmission devices having various speed ratios as between said drive shaft and the related internal gear, said transmission devices being readily removable and interchangeable whereby the resultant speeds of the several figures in the case of any chance arrangement of the transmission devices is unknown to the players of the game.

8. In a racing game, a support surface having a closed race course at its upper surface with figures movable thereon to traverse such race course, coaxial internal gears and means extending from each of said gears to one of said figures for propelling the latter upon rotation of the former, a drive shaft disposed within the internal gears and spring motor means for rotating the same, and a plurality of transmission devices each adapted to establish driving connection between said drive shaft and an internal gear, said several transmission devices each having a central sun gear slidably keyed to said drive shaft and a planet pinion meshing with said sun gear and an internal gear, the several pairs of sun gears and planet pinions being of different drive ratios, said internal gears being of the same pitch diameter and tooth size and said transmission devices being readily removable and interchangeable whereby the resultant speed of the several figures in any random arrangement of the transmission devices is unknown to the players of the game, means for

manually winding said spring motor, and selectively operable means for releasing the same to rotate said drive shaft and thus simultaneously propel the several figures.

9. In a racing game, a support surface having a closed race course at its upper surface with figures movable thereon to traverse such race course, coaxial internal gears and means extending from each of said gears to one of said figures for propelling the latter upon rotation of the former, a drive member and spring motor means for rotating the same, and a plurality of similar transmission devices each adapted to lie generally in the plane of one of said internal gears to establish driving connection between said drive member and such internal gear, said several transmission device having various speed ratios as between said drive member and the related internal gear, said transmission devices being readily removable and interchangeable whereby the resultant speeds of the several figures in the case of any chance arrangement of the transmission devices is unknown to the players of the game, means for manually winding said spring motor, and selectively operable means for releasing the same to rotate said drive member.

10. In a racing game, a support surface having figures movable thereon, coaxial internal gears and coaxial freely rotated wheel members spaced from but coplanar with the several internal gears, endless flexible member extending about each gear and its coplanar wheel member, means extending from each of said flexible members to one of said figures for propelling the latter in oblong paths having semicircular ends, a drive shaft disposed within the internal gears and means for rotating the same, and a plurality of transmission devices each adapted to establish driving connection between said drive shaft and an internal gear, said several transmission devices each having a central sun gear slidably keyed to said drive shaft and a planet pinion meshing with said sun gear and an internal gear, the several pairs of sun gears and planet pinions being of different drive ratios, said internal gears being of the same pitch diameter and tooth size and said transmission devices being readily removable and interchangeable whereby the resultant speed of the several figures in any random arrangement of the transmission devices is unknown to the players of the game.

11. In a racing game, a support surface having figures movable thereon, coaxial internal gears and coaxial freely rotated wheel members spaced from but coplanar with the several internal gears, endless flexible members extending about each gear and its coplanar wheel member, means extending from each of said flexible members to one of said figures for propelling the latter in oblong paths having semi-circular ends, a drive member and means for rotating the same, and a plurality of similar transmission devices each adapted to lie generally in the plane of one said internal gears to establish driving connection between said drive member and such internal gear, said several transmission devices having various speed ratios as between said drive member and the related internal gear, said transmission devices being readily removable and interchangeable whereby the resultant speeds of the several figures in the case of any chance arrangement of the transmission devices is unknown to the players of the game.
